MANIFOLDING DEVICE

Milton C. Stern and William C. Pfeiffer, Dayton,
Ohio, assignors to The Egry Register Company,
Dayton, Ohio, a corporation of Ohio

Application January 14, 1936, Serial No. 59,114

42 Claims. (Cl. 197—126)

This invention relates to manifolding devices, and in particular, to devices employing copying materials such as ribbons or carbons for making multiple copies of documents, especially those used in connection with typing, adding and tabulating machines and the like.

One object of this invention is to provide a manifolding device employing copying ribbons either alone or with carbon strips having means 10 to prevent the adhesion of the copying ribbons to the multiple paper sheets whereby the ribbons are caused to start moving before the paper sheets or webs begin their motion, and to continue their motion after the paper has ceased moving. 15 Optionally, carbon strips are additionally provided, with appropriate mechanism therefor to cooperate with the ribbons and amplify their action so as to produce a number of copies in excess of the number conveniently produced by the 20 ribbons alone; these carbon strips being either in sheets or in continuous webs.

Another object is to provide a manifolding device wherein the paper sheets and the copying ribbons are moved intermittently relatively to the 25 typing mechanism so that the ribbons and paper are stationary while the imprint is being made, yet move to new positions after the printing has been completed.

Another object is to provide a manifolding device having a plurality of duplicating or copying ribbons interleaved between a plurality of paper webs, means being provided to prevent the ribbons from moving in the direction of motion of the webs by adhesion thereto; this adhesion being 30 prevented by causing the ribbons to start their motion before the paper moves, and to continue their motion after the paper stops moving.

Another object is to provide a manifolding attachment for a tabulating, adding or similar machine, which prints records, the attachment being connected to the machine in such a manner as to 35 operate synchronously with the machine.

Another object is to provide a platen mechanism for interconnecting the manifolding attachment 40 of this invention with the machine to which it is to be attached, this platen mechanism serving as the connection for synchronizing the machine and the attachment.

Another object is to provide a manifolding attachment which may be optionally lowered into engagement with the machine or raised out of engagement therewith, so as to lift the machine free for use or adjustment independently of the attachment.

Another object is to provide a manifolding at-

tachment for use with a tabulating machine, the attachment having means employing duplicating or copying ribbons cooperating with the typing already written upon the tabulating machine to produce additional copies of the tabulated records, 5 other than the single copy ordinarily produced by the tabulating machine.

Another object is to provide a manifolding attachment having a motor with devices for feeding the paper sheets and the copying ribbons at a time 10 when the typing mechanism of the tabulating machine is at rest, and while the analyzing mechanism of the machine is being operated to set the totalizer thereof for a new typing operation, the devices being arranged to cause the attachment 15 motor to stop during the time while the printing or typing mechanism of the totalizer causes an imprint upon the paper sheets and copying ribbons.

Another object is to provide a manifolding attachment 20 wherein copying ribbons are interleaved between the paper webs, a single copy ribbon being caused to be twice interleaved by being passed to and fro between the webs in reverse directions, the ribbon at one limit of its motion having a 25 guide roller or similar means for causing it to reverse its direction of motion.

Another object is to provide a manifolding device having means positively engaging the file punch holes, such as pins upon chains positively 30 driven by mechanism synchronized with the printing mechanism of the machine to which the device is attached, the paper webs or sheets being interleaved by copying or duplicating ribbons traveling in a transverse direction to the direction 35 of motion of the paper, or by carbon strips.

Another object is to provide a manifolding device having mechanism for the step-by-step feeding of a plurality of copying or duplicating ribbons interleaved between a plurality of moving paper webs, together with mechanism for synchronizing the feeding of the ribbons and the paper webs 40 with the printing mechanism of the machine in connection with which the manifolding device is employed.

Another object is to provide a manifolding device employing a plurality of copying ribbons which are interleaved between and moved in a direction perpendicular to the direction of motion of multiple paper webs, means being provided 50 to cause the ribbons to automatically reverse their direction of travel when the ribbon reaches a predetermined position, such as when the supply of ribbon on one spool has diminished to a predetermined extent.

Another object is to provide an attachment for a tabulating machine consisting of a plurality of fingers arranged to control and position the master ribbon of the printing portion of the machine so that it may cooperate with additional copying ribbons employed in a manifolding attachment used in connection therewith.

Another object is to provide a manifolding device having multiple copying ribbons, these ribbons being guided by means mounted upon a movable carriage and interleaved between multiple paper sheets or webs, the carriage in one location being arranged to permit the paper webs to be easily threaded between the ribbons, and in another location to be placed in the printing position, the carriage in the printing position being preferably arranged to put the copying ribbons under the proper tension.

Another object is to provide a manifolding device having copying ribbons caused, in different portions of their length, to move perpendicularly, means being provided to change the direction of motion for this purpose; each ribbon being caused to move from one side of the machine to the other side around a guide, and thence back again across the machine so that a single ribbon accomplishes the purpose of a plurality of ribbons.

Another object is to provide a manifolding device having positive feeding means engaging multiple paper webs, as by perforations therein, this positive feeding means being synchronized to be moved by a motor, the operation of which is controlled by connecting mechanism operated by the printing machine in connection with which the device is used, the same mechanism also controlling the motion of multiple duplicating ribbons interleaved between the paper sheets or webs.

Another object is to provide a manifolding device which is pivotally arranged to be swung from an operative to an inoperative position, together with a container mounted on the frame for receiving the paper sheets or webs after they have been printed, with means for holding this container in position.

45 In the drawings:

Figure 1 is a general view, in front elevation, of the manifolding device of this invention, mounted upon and cooperating with the printing portion of a tabulating and listing machine.

50 Figure 2 is an enlarged view, in front elevation, of the manifolding device and the adjacent portion of the tabulating and listing machine as shown in the upper right-hand corner of Figure 1, with a portion of the casing removed to disclose the contents, and with the ribbon carriage of the manifolding device raised out of the printing position.

Figure 32 is a vertical section through the printing portion of the machine taken along the 75

line 32—32 of Figure 1, and showing the copying ribbons in position relatively with respect to the master ribbon.

Figure 33 is a section taken on the line 33—33 of Figure 1, showing the devices of Figure 32 in top plan view.

Figure 34 is an enlarged front elevation of the paper webs and the copying ribbons.

Figure 35 is a horizontal section through the platen of the machine, the master ribbon and the copying ribbons.

Figure 36 is a fragmentary view of the middle portion of Figure 11, with the upper part in section along the line 36—36 in Figure 30.

Figure 37 is a horizontal section along the line 37—37 in Figure 11, showing the sliding gear and the clutch finger in the closed position.

Figure 38 is a vertical section along the line 38—38 in Figure 37.

Figure 39 is a view similar to Figure 37, but showing the sliding gear and the clutch finger in the partially open position, with the open position dotted.

Figure 40 is a plan view, partly in section, taken along the line 40—40 in Figure 31.

Figure 41 is a diagrammatic view of a modified portion of Figure 32, showing the employment of carbon strips to produce additional copies in excess of those provided by the copying ribbons.

30 General construction

In general, the manifolding device of this invention, as shown in the upper right-hand corner of Figure 1, is an attachment to be used in conjunction with some machine capable of typing or printing a record, especially a numerical record. The main machine ordinarily possesses its own ribbon in connection with its printing type, and the manifolding device is intended to supplement the action of the main ribbon by providing multiple copies of the record printed by the type bars and the main ribbon.

Hitherto, devices used in connection with such machines have ordinarily employed carbon sheets interleaved between multiple paper sheets or webs. These carbon sheets were moved with the paper sheets, and after a short time wore out and required replacement. The carbon sheets also interfered with the alignment of the paper sheets and required some means for being moved to and fro after a certain length of paper was typed so as to bring the carbon sheets into engagement with an untyped series of paper sheets or webs.

In the manifolding device of the present invention, however, the multiple copies are made by copying or duplicating ribbons interleaved between the multiple paper sheets and traveling in a direction perpendicular to the direction of motion of the sheets or webs. Ordinarily, the adhesion of the ribbons to the paper prevents the successful use of copying ribbons, where these ribbons must move in a direction transverse to the direction of motion of the paper. In the present invention, however this difficulty has been overcome by providing mechanism which causes the copying ribbons to start their motion before the paper webs or sheets commence to move, the motion of the ribbons being continued for a short period after the paper webs have stopped moving. This provision eliminates the adhesion between the paper webs and the ribbons, and prevents the ribbons from being carried upward with the paper and out of registry with the type bars.

The manifolding device of the present invention is connected to the mechanism of the machine to which it is attached so that its motor and driving mechanism are synchronized to operate at the proper times with respect to the operation of the machine as a whole. This connection is made through mechanism attached to the left end of the platen, as viewed in Figures 1 and 2, this mechanism controlling the starting and stopping of the motor which feeds the paper webs and moves the copying ribbons. The machine with which the manifolding device is used may be of any suitable type which prints a record of which multiple copies are desired.

In the embodiment disclosed herein a machine of the type known as a tabulating and listing machine is shown for purposes of illustration (Figure 1). This machine is of a conventional type and employs cards which are punched with apertures in different positions, according to the data recorded on the particular card. The cards are then fed into the left-hand end of the machine at the delivery point 1, and pass downward through the portion 2. At the latter location the cards are subjected to certain mechanism which automatically analyzes the data recorded on the card, this data being added or otherwise operated upon by mechanism between the portions 3 of the machine, the totals appearing in the windows 4 thereof.

After being thus analyzed the cards 5 drop downwardly into a movable holder 6, beneath the portion 2, where they accumulate and cause the holder 6 to move and accommodate more cards. Counterweights 7 assist in regulating the position of the holder 6. A motor 8 serves to operate the tabulating machine shown, in response to the depression of the operating keys 9, 10 or 11. The various mechanism sections 3 are interconnected by shaft portions 12, terminating in a portion 13 which enters the printing or listing section 14 of the machine. This section is likewise controlled by the starting push button 15, the stopping push button 16 and the resetting push button 17. A clutch shaft 18, operated by a hand lever 19, serves selectively to connect or disconnect the printing section 14 from the remainder of the machine so that the machine may be operated either to tabulate the results without printing, or to print the results as well as to tabulate them. The printing section 14 of the machine (Figure 2) likewise contains mechanism of a conventional type, the details of which are well known to those skilled in the art.

The printing mechanism culminates in type bars 20 (Figures 2, 32 and 33) having type thereon for printing different letters, numerals or characters. These type bars 20 are operated by mechanism connected with the mechanism in the portions 3 and correlated to give printed records of the totals indicated in the windows 4. To this end a master ribbon 21 cooperates with the type bars 20 to furnish the master record of the machine. The master ribbon 21 is connected at its opposite ends to spools 22 and 23, supported on the shafts 24 and 25, and regulated as to their reversal by the T-lever 26 (Figure 2). The latter is pivoted, as at 27, and carries portions on its opposite ends engaging the ribbon and caused to move to and fro when the end of the ribbon is indicated by a knot, or other projection. The vertical part of the T-lever 26 is joined to a connecting rod 28, which serves to control mechanism for causing the spool 22 or the spool 23 to be driven according to the position of the T-lever 26.

The master ribbon 21 is guided at suitable intervals in its path by the guide rollers 29. The shafts 24 and 25 for carrying the ribbon spools 22 and 23 are supported in a framework, generally designated 30, and supported by the printing section 14. A cover plate 31 serves to inclose the printing mechanism, and is provided with a guide plate 32 having downwardly extending ribbon fingers 33 for holding the master ribbon 21 in position 10 and preventing it from rising or falling.

The machine is likewise provided with a platen 34, mounted in a suitable frame having end plates 35 and 36 and tie rods 37 (Figure 2). The platen 34 is provided with gripping rollers 38 mounted 15 upon the arms 39, attached to the gripping roller shaft 40 and arranged to be moved into or out of engagement with the platen 34 by the action of the hand lever 41 connected to the operating shaft 42 thereof. When the hand lever 41 is in the 20 lower position shown in Figure 2, the gripping rollers are out of engagement with the platen 34. If, however, the hand lever 41 is raised it causes the gripping rollers 38 to engage the platen 34. When used with the manifolding device of 25 the present invention, however, the gripping rollers 38 are maintained out of engagement with the platen 34 so that the platen itself exerts no aligning function. The alignment of the various paper forms is provided by mechanism within the 30 manifolding device itself and not within the machine to which the device is attached.

The platen 34 is mounted upon the platen shaft 43 (Figure 2) and rotated manually by the knobs 44 and 45. The right-hand end of the platen 35 shaft 43 is driven by gearing, subsequently to be described, and communicating power thereto from the manifolding device shown in the upper part of Figure 2. The left end of the platen shaft adjacent the end plate 35 carries the mechanism 40 by which the machine and the manifolding device are interconnected and synchronized. The platen 34 may be moved to and fro laterally, as is usual in such machines, and when it is so moved the manifolding attachment moves with it. This 45 motion is provided in order to adjust the position of the printing upon the particular paper form or web. The platen 34 is cut away at its ends to provide slightly reduced diameter portions 46, which serve to permit the copying ribbons to more 50 closely approach the platen, as will be described subsequently.

The left end of the platen shaft 43 carries a disc 47 (Figure 18) having pins 48 surrounded by coil springs 49 bearing against the end of the 55 platen 34. By this means the platen 34 may be adjusted longitudinally along its shaft 43, while the disc 47 remains stationary. Secured to the disc 47 is a ratchet wheel 50 by which the platen 34 may be revolved step by step by the usual 60 pawl and ratchet mechanism. This mechanism is shown only incidentally because it is not made use of in the operation of the manifolding device of this invention. As previously stated, the gripping rollers 38 are held out of contact with the 65 platen 34 during the operation of the manifolding device, and hence, the operation of the platen ratchet 50 will have no effect upon the feeding of the paper webs, this being controlled by means within the manifolding device.

70 The pawl 51, the upper end of which is shown in Figure 18, is pivoted on the pin 52 and is, in turn, mounted upon the arm 53 pivoted on the platen shaft 43. The pawl 51 is held in engagement with the ratchet 50 by the spring 54. The 75 pawl arm 53 at its outer end, near the pawl pivot

pin 52, carries a pin 55 which is engaged by a forked arm 56 for raising and lowering the pawl arm 53 and the pawl 51 as the forked arm 56 is moved up and down. The forked arm 56 is attached to a bracket 57 secured to the pivot shaft 58, extending between the platen end plates 35 and 36. Through the outer end of the bracket 57 passes the cross shaft 59, which runs parallel to the pivot shaft 58 and is capable of being moved up and down around the pivot shaft 58. 10

As the cross shaft 59 moves up and down the bracket 57 and the forked arm 56 pivot around the pivot shaft 58. The outer end of the forked arm 56 engages the pin 55 on the pawl arm 53, causing the pawl 51 to move up and down and move the ratchet 50 one notch for each stroke of the cross shaft 59. A roller 60, carried by the arm 61, serves as a detent engaging the ratchet 50, the arm 61 being pivoted around the pivot pin 62 supported by the stud 63 mounted on the 20 platen end plate 35. The lever 64 carries a projection 65 which engages the pawl 51 to cause it to move selectively through a distance representing either one or two notches of the ratchet 50, thereby providing for single or double space 25 motion of the platen 34. The spring 66 serves to hold the lever 64 in either of its adjusted positions, whereas the spring 67 holds the roller 60 of the arm 61 in engagement with the ratchet 50. This platen rotating mechanism (Figure 18), as 30 stated above, is not employed when the manifolding device is in use because it is operated ineffectively by reason of the fact that the gripping rollers 38 are out of engagement with the platen 34. 35

Mechanism for synchronizing manifolding device with printing machine

The cross shaft 59 is given its up and down motion by a link 68 pivoted thereto at its upper 40 end (Figures 17 and 18), the lower end being pivotally connected, as by the bolt 69, to the rocker arm 70 (Figure 17). The rocker arm 70 is pivotally supported at an intermediate point by the bolt 71, and has a connecting rod 72 secured to its outer end, as by the bolt 73. A slot 74 in the connecting rod 72 provides an adjustment whereby the position of the rocker arm 70 may be varied with respect to the connecting 45 rod 72. The connecting rod 72 is operatively connected to the mechanism within the printing section 14 of the machine and moves up or down 50 in response to the action of this mechanism. The pivot bolt 71 is mounted upon the frame of the printing section 14, assisted by the supporting bracket 75. Accordingly, as the connecting rod 72 moves up and down intermittently in synchronization with the printing mechanism of the machine, the link 68 will likewise be moved up and down to actuate the pawl 51 and move the 60 platen 34 either through single notches or double notches of the ratchet 50, as controlled by the setting of the lever 64. Figure 17 shows the link 68 in its raised position, whereas Figure 16 shows the link 68 in its lowered position. 65

Mounted for reciprocation vertically on the platen end plate 35 is a J-shaped member 76 (Figure 17), having its lower end 77 extending beneath the platen end plate 35 and forked to engage the cross shaft 59 (Figure 15). The slot 78, cooperating with the pin 79, guides the J-shaped member 76, in its vertical reciprocation, and the spring 80 connected between the pin 79 and the pin 81, near the lower end of the member 76, urges the latter into an upward 75

position and accordingly urges the cross shaft 59 into an upward position. Mounted on the upper right-hand corner of the J-shaped member 76 is a stud 82, which is engaged by the 5 forked end 83 of the lever 84. The latter is pivotally mounted upon the platen shaft 43 (Figures 16, 17 and 18), and at its opposite end is provided with teeth 85 adapted to mesh with the corresponding teeth of a pinion 86, rigidly 10 secured to the lever 87. The latter is pivotally mounted on the pin 88, supported by the supporting arm 89 mounted on the platen end plate, as by the screws 90. The latter also support a guide plate 91, serving to guide the motion of 15 the ratchet operating lever 92. The latter is pivoted at its upper left-hand corner around the pin 79 and is provided with a cam surface 93 adapted to engage the pin 81 on the lower part of the J-shaped member 76.

20 By moving the ratchet operating lever 92 from its upper position (Figure 17) to its lower position (Figure 16) the J-shaped member 76 may be moved up and down, and with it the cross shaft 59, thereby operating the pawl 51 to move 25 the platen ratchet 50 by single or double notches, according to the setting of the lever 64. At the same time, however, it will be seen that the operation of the lever 84, through its engagement with the stud 82 on the J-shaped member 76, will 30 cause the lever 87 to move outward into the position shown in Figure 16 by reason of the intermeshing of the teeth upon the end of the lever 84 and the pinion 86. The lever 87 is connected to the motor operating switch and clutch 35 of the manifolding device, in a manner subsequently to be described and in such a way that when the lever 87 is in its inward position, shown in Figure 17, the motor is energized and the paper-feeding mechanism caused to operate. When the 40 lever 87 is in its outward position, shown in Figure 16, however, the manifolding device motor is deenergized and the paper-feeding mechanism accordingly halted. Thus, as the platen ratchet 50 is operated manually by the hand lever 92 the 45 manifolding device motor is automatically disconnected. Similarly, when the link 68 is moved up or down by the action of the rocker arm 70 during the printing operation, the J-shaped member 76 is likewise moved up and down, and the 50 lever 87 moved in and out to energize and de-energize the manifolding device motor, respectively, but the hand lever 92 remains motionless because it merely has a contacting engagement between its cam surface 93 and the pin 81. 55 By this means the motor of the manifolding device is caused to operate in synchronism with the printing section 14 of the machine.

Manifolding device frame and driving mechanism

60 The manifolding device of this invention is supported upon a table-like structure 94 (Figures 5 and 6), having a top 95 and legs 96. A shelf 97 serves to support a pack 98 of folded multiple paper forms before they are ready for printing. 65 The paper webs, generally designated 99, are folded in a zigzag manner in the pack 98. The paper webs 99 pass upward through a cutaway portion or slot 100 in the table top 95 (Figure 6), over a rod 101 and into engagement with the platen 34. The rod 101 is supported by the U-shaped frame upright 102, secured to the table top 95 by the bolts 103. The rod 101 is engaged by its opposite ends by the hand wheels 104, which serve selectively to halt or release the manifolding device supported thereby.

The manifolding device is supported by frame side members 105 (Figures 4 and 5), having cross arms 106 interconnecting them for bracing purposes and for supporting a container 107 for receiving the printed paper forms. The container 10 is shown as a basket, but may consist of a box or other suitable receptacle for the paper webs after they have been subjected to the printing action of the printing section 14. The side members 105 serve to support the entire manifolding device and are pivotally mounted upon the shaft 101 in such a manner that the device may be placed in its upright or operative position, shown in solid lines (Figures 5 and 6), or in its operative inverted position, as may be 15 desired. When so inverted the frame side members 105 rest upon resilient blocks 108, mounted upon the supports 109 on each side of the table top 95, as by the bolts 110. Mounted on the left-hand side member 105 is a bracket 111, having 20 a resilient pad 112 serving to support the motor 113 for driving the manifolding device. The drive shaft 114 is joined by the resilient connection 115 to the motor drive casing 116. Beyond the resilient connection 115 the drive shaft continues in a portion 117 (Figure 6). The latter enters the motor drive casing 116 and carries on its lower end a worm 118, the worm 118 meshing with a worm gear 119 (Figure 6).

The worm gear 119 is provided with clutch 30 mechanism for selectively connecting and disconnecting it with the output shaft 120 (Figure 31). The mechanism within the motor drive casing 116 forms no part of the present invention, and is completely disclosed in the United States Patent, No. 1,825,418, to Frank E. Pfeiffer, et al., dated September 29, 1931. The casing 116 also contains a switch for energizing and de-energizing the motor 113, the switch and clutch being simultaneously operated by the operating 40 lever 121 extending downwardly from the casing 116 (Figures 2 and 6).

The operating lever 121 is provided with a projecting pin 122 adapted to be engaged by the corresponding notch 123 in the lever 87, mounted 45 on the end plate 35 of the platen (Figures 16 and 17). Accordingly, when the lever 87 moves to and fro as the link 68 moves up and down, the motor 113 will be energized or deenergized and connected with or disconnected from the output shaft 120. The mechanism within the casing 116 is so arranged, as disclosed in the above mentioned patent, that the clutch will be opened so that the motor will spin to a stop, when the operating lever is moved by the motion of the lever 50 87. At the same time the operating lever carries a tab 124, whereby it may be operated manually (Figure 2). The mechanism within the casing 116 is also so arranged that it executes a complete cycle of rotation regardless of when the lever 60 121 is released, so that the paper sheets or webs 99 will be fed only through whole spaces and not partial spaces, thereby preventing one set of webs from partially overlapping another set.

Paper feeding mechanism

The frame side members 105 are interconnected by a cross bar 125 (Figure 3), carrying frame uprights 126. These uprights are of channel or U-shaped cross section, and at their upper ends 70 carry slotted brackets 127 inserted therein, and held in position by the bolts 128 passing through the slots 129. The brackets 127 at their upper ends are bored to rotatably support the shaft 130. The latter is provided with a plurality of 75

drums 131, over which the paper webs 99 pass. The shaft 130 also is provided with a pair of sprockets 132, carrying sprocket chains 133 provided at suitable intervals with studs 134. The 5 studs 134, as hereinafter disclosed, serve to enter the file punch holes, which are arranged at proper intervals along the paper webs and serve to positively engage the paper webs 99 without the possibility of slippage. The cross bar 125 also 10 carries a plate 135 (Figures 3 and 4), secured thereto by the screw 136 and having the upwardly extending paper guide fingers 137. A pressure roller 300 (Figures 9 and 19) supported by the ribbon carriage 175 serves to force the 15 paper webs upon the aligning pins 134 and is annularly grooved to permit the passage of the pins, (Figures 4 and 9).

The sprocket chains 133 at their lower portions pass around sprockets 138 mounted on the 20 sprocket drive shaft 139 (Figure 9). The latter shaft is coaxial with the output shaft 120 of the motor drive casing 116, but rotatable independently thereof, and connected thereto by a ratchet mechanism shown in Figures 28 and 31. By 25 this ratchet mechanism the paper webs 99 are fed around the platen by predetermined steps. For this purpose the output shaft 120 from the casing 116 is provided with a gear 140 (Figure 31), secured thereto and having a pin 141 projecting toward the casing 116. The left-hand side member 105 also serves to support a stud 142, which carries the idler gear 143 and also pivotally supports the pawl-operating arm 144. The latter at its opposite end is provided with a pin 145, which 30 serves as a pivotal connection for the pawl 146. The pawl 146 is urged into engagement with the ratchet wheel 147 by the spring 148. The ratchet wheel 147 is mounted upon the sprocket shaft 139 and serves to rotate the sprockets 138 and move 35 the sprocket chains 133 in response to the action of the pawl 146.

Also mounted upon the left-hand frame side member 105 is a pin 149, serving as a pivotal support for the detent 150. The latter at its outer 40 end is provided with a pin 151, carrying one end of a coil spring 152, the opposite end being connected to a pin 153 upon the pawl 146. The detent 150 thus serves to prevent slippage of the ratchet 147 in the interval between successive 45 engagements of the pawl 146. The frame side member 105 is provided with a pin 154, which serves as a pivotal mounting for the hand lever 155, having a cam portion 156 arranged to engage the lower side of the pawl-operating arm 144.

50 When the lever 155 is in its raised position, as shown in Figure 29, this cam portion engages the arm 144 at the position nearest the axis of the pivot point 154 so that the arm 144 is permitted to approach its lowermost position, in which position it is adapted, when operated, to cause the pawl 146 to move the ratchet wheel 147 through two spaces. In other words, in this position the pin 141 on the gear 140 is caused to engage the pawl-operating arm 144 through a greater range 55 than when the lever 155 is pushed downward to its lowest position. In the latter case the cam portion 156 raises the pawl-operating arm 144 to its "single space" position so that the gear pin 141 engages it over a smaller range, and accordingly, 60 lifts the pawl 146 to cause the ratchet wheel 147 to move through a single space.

65 As the output shaft 120 is caused to rotate by the operation of the motor 113, in response to the actuation of the hand control lever 121 thereof by 70 the platen mechanism, the gear 140 likewise ro-

tates, carrying its pin 141 into engagement with the pawl-operating arm 144 during a partial revolution thereof. During the entire revolution, however, the idler gear 143 is rotated by its intermeshing engagement with the gear 140, and this, in turn, rotates the ribbon driving gear 144 carried by the ribbon-operating shaft 157 mounted between the side members 105. As will subsequently be seen, the ribbons driven by the shaft 157 through the gears 144, 143 and 140 are started 10 in motion before the paper webs 99 are caused to move by the action of the ratchet wheel 147. After the paper webs have ceased moving, when the gear pin 141 has passed beneath the pawl-operating arm 144 (Figure 31), the ribbons 15 nevertheless continue to move as long as the shaft 120 continues to rotate. By this means the copying or duplicating ribbons are caused to start moving before the paper webs start, and continue to move after the paper webs stop, thereby preventing the adhesion and "bowing up" of the ribbons which might otherwise occur by the friction or sticking of the paper webs and the ribbons. 20

Platen driving mechanism

25

The sprocket shaft 139 on the end opposite the ratchet wheel 147 carries a collar 158 (Figure 11) rigidly secured thereto, and having a pin 159 pivotally supporting a clutch finger 160. The sprocket shaft 139 at this point carries a sliding gear 161 (Figure 30) having a hub 162, within which is a coil spring 163 for urging the gear 161 toward the end of the sprocket shaft 139. The gear 161 is provided with slots 164 (Figure 11) in its outer face, and adapted to be engaged by 35 one end of the clutch finger 160 when the latter is moved into the position shown in Figures 11 and 30. When the outer end of the clutch finger 160 is moved toward the center of the sprocket shaft 139, however, the sliding gear 161 is moved 40 backward and its slots 164 moved out of engagement with the clutch finger 160. In this position the gear 161 rotates loosely upon the sprocket shaft 139 without a driving engagement therebetween. Consequently, by manipulating the 45 clutch finger 160, the sprocket shaft 139 may be caused to rotate the gear 161 or not, as may be desired.

The gear 161 meshes with an idler gear 165 mounted upon a stud 166, which in turn, is supported on the lower end of a quadrant 167, the upper end of which is pivotally mounted upon the sprocket shaft 139. The quadrant 167 is provided with an arcuate slot 168 (Figure 7), with its center of curvature on the axis of the sprocket 55 shaft 139. A screw 169, passing through this slot and threaded into the right-hand frame side member 105, serves to lock the quadrant 167 and its gear 165 in any position of adjustment within the range of the arcuate slot 168. The gears 60 161 and 165 and the quadrant 167 are covered by a cover casing 170, secured to the side member 105 by the screws 171. The cover casing 170 is provided at its lower end with an arcuate slot 172 of sufficient width to pass around the 65 platen shaft 43, and with its center of curvature coincident with the axis of the shaft 101 supporting the manifolding device upon the uprights 102.

The platen shaft 43 is provided with a gear 173 70 arranged to mesh with the idler gear 165, and serving to drive the platen shaft 43 when the power is communicated to the gear 161 from the sprocket shaft 139, through the clutch collar 158 and clutch finger 160. In this manner the platen 75

34 is rotated in synchronism with the sprockets 132 and 138 carrying the sprocket chains 133 with the studs 134 which move the paper webs 99. The arcuate slot 172 permits the manifolding device to be inserted downwardly over the platen shaft 43 or instantly raised and turned backward into its inoperative position, as shown in Figure 16, this action taking place around the shaft 191 as a pivot. With the apparatus in its inoperative position, as shown by the dotted lines in Figures 5 and 6, it is found most convenient to thread the paper webs 99 between the copying ribbons, as described below.

15 *Ribbon driving, reversing and guiding means*

In the manifolding device of the present invention multiple ribbons are employed for performing the duplicating function. These ribbons are arranged upon spools, pass downwardly through the apparatus, are guided at various points along their paths and return to spools on the same side of the machine, after passing completely across the machine and back again. For this purpose the frame side members 105 are provided with grooved guide members 174 (Figure 3) of U-shaped cross section. These guide members serve to receive the ends of the ribbon carriage 175 for vertical reciprocation. The ribbon carriage 175 is provided with pivoted latch members 176 which are arranged to engage upper notches 177 and lower notches 178 in the guide members 174, thereby holding the ribbon carriage 175 in an upper or a lower position. In the upper position the ribbons are in a position where they may be more easily threaded and adjusted, whereas in the lower position the ribbons are properly located in front of the platen for the printing operation.

The ribbon carriage is provided with downwardly depending ribbon supports, generally designated 179. Each ribbon support 179 consists of a plate secured to the ribbon carriage 175 at its upper end, and having a pair of vertical grooves 180 and 181 therein (Figure 13). The ribbon supports 179 extend upwardly behind the ribbon carriage and at their top ends, above each groove, are supplied with loosely rotatable guide rollers 182 (Figures 21 and 22). The grooves 180 and 181 are separated from one another by a vertical ridge 183, and are bounded on their outer edges by the vertical ridges 184 and 185. The view shown in Figure 13 is that of the right-hand ribbon support of Figure 3, the left-hand ribbon support being substantially a duplicate, but with its construction reversed from left to right. In either case the ridges 184 and 185 terminate at a location short of the bottom cross member 186, the space therebetween being occupied by rotatable rollers 187 and 188.

60 The roller 187 is of cylindrical form. The roller 188, however, in the right-hand ribbon support 179, is of conical form, whereas the left-hand roller of the left-hand ribbon support 179 is of spindle shape. The rollers 189 serve to reverse the course of each ribbon as it proceeds to and fro across the front of the machine. The cylindrical roller 187 is the inner roller in each of the ribbon supports 179, it being the right-hand roller of the left-hand support in Figure 3 and the left-hand roller of the right-hand support.

65 The center ridge 183 also terminates on the same level as the side ridges 184 and 185, but the bottom surface of the groove 180 continues downwardly beneath it to join the bottom cross mem-

ber 186. The bottom portions of the grooves 180 and 181 are cut off to form diagonal edges 189 and 190, these edges being rounded to permit easy and smooth passage of the ribbons therearound. Each ribbon is supported at each end upon a 5 spool. These spools are separately designated 191, 192, 193 and 194 for convenience of tracing the paths of the respective ribbons. The details of driving the respective ribbon spools will be described below, these spools being mounted upon 10 the ribbon shaft 157 at the rear of the device (Figure 4).

From Figures 4 and 3 it will be seen that the ribbon 195 proceeds from its spool 191 upwardly on a diagonal line, over the guide roller 196, 15 thence downwardly through the groove 181, around the diagonal edge 190, behind the left-hand ribbon support 179 (Figure 12), across the front of the machine, behind the right-hand ribbon support 179, and around the conical roller 20 188. Reversing its path at the roller 188, the ribbon returns behind the right-hand ribbon support 179 to the left-hand ribbon support 179, around the diagonal edge 189, up the vertical groove 180, over the guide roller 197 and downwardly in a diagonal path to the spool 192. The ribbon 198, however, proceeds from the spool 194, over the guide roller 199, downwardly through the groove 181 of the right-hand ribbon support 179, around the diagonal edge 190 and 30 behind the remainder of the ribbon support, thence across the front of the device, over the front of the left-hand ribbon support 179, around the spindle-shaped roller 188, back across the front of the device to the right-hand ribbon support 179, around the diagonal edge 189, up the groove 180, over the guide roller 200 and downwardly to the spool 193. Accordingly, the opposite ends of each ribbon are attached to adjacent spools on each side of the machine, the 40 ribbon making a double loop as it passes across the front of the machine.

The guide rollers 196, 197, 199 and 200 are supported upon shafts 201 mounted in the side plates 202, secured to the frame cross bar 125. 45 The side plates 202 extend downwardly and form a framework for supporting the ribbon-driving mechanism, as will subsequently appear. Arms 203 pivoted on the shafts 201 serve to support floating guide rollers 204, which press downwardly 50 against the ribbons and assist in maintaining a taut condition thereof. The ribbon carriage 175 also serves to support the upwardly extending paper guide rods 205, interconnected by the cross member 206. The paper guide rods 205 55 are shaped roughly like a question mark, the straight portions thereof serving to hold the punch holes of the paper over the studs 134 on the sprocket chains 133. The upper portions curve over the paper guide drums 131 and serve 60 to assist in reversing the course of the paper.

The ribbon spools 191, 192, 193 and 194 are loosely mounted for free rotation upon the ribbon shaft 157, which is driven by the gear 144 (Figure 31), through the idler gear 143 from 65 the gear 140 on the output shaft 129 of the motor drive casing 116. The ribbon spools on their outer sides have teeth drivingly engaged by the teeth 207 or 208 of a sliding gear, generally designated 209 (Figures 4 and 20 to 27). For convenience, the drive of the ribbon spools 193 and 194 will be described, the ribbon spools 191 and 192, (Figure 4), being similarly driven.

70 The ribbon shaft 157 (Figure 19) carries a gear 210, which meshes with and drives an idler 75

gear 211 upon the stud 212, mounted on one of the side plates 202. The idler gear 211 meshes with and drives a second idler gear 213 on a stud 214, similarly mounted on the same side plate 202. The idler gear 213 meshes with and drives a gear 215, mounted on the shaft 216 extending between the side plates 202 (Figures 19 and 20). The shaft 216 drives the sliding gear 209 by means of its pin 217 (Figure 26) engaging the slot 218 in the sliding gear 209. A spring 296 urges a ball detent 297 (Figure 26) into one of the two depressions 298 or 299 when the gear 209 is shifted to the right or to the left.

The sliding gear 209 is provided with a pair of cam ridges 219 and 220, with vertically movable pins 221 and 222 supported therebeneath in brackets 223 attached to the end plate 224, interconnecting the side plates 202 (Figures 21, 24 and 26). Each of the pins 221 is provided with lower and upper flanges 225 and 226, respectively. Beneath the lower flange 225 is a coil spring 227, having its opposite end engaging the lower bracket 223. These coil springs 227 serve to urge the pins 221 in an upward direction. The motion 25 of the pins 221 downward is limited by the projecting lugs 228 of the end plate 224. The flanges 225 and 226 are of annular form and are firmly secured to the pins 221. The left-hand flange 225 is engaged by an irregularly shaped bellcrank 30 lever 229, which passes through slots 230 and 231 in the end plate 224 (Figure 25), and is pivoted loosely on the ribbon shaft 157 (Figure 19). The other arm of this bellcrank lever continues upward from this pivot and closely approaches 35 one of the side plates 202. Its upper edge is arranged to be engaged by a button 232 upon an arm 233, pivoted on the shaft 234 to the side plate 202. The outer end of the arm 233 carries a slotted pin 235 (Figure 20), through which the 40 ribbon passes.

Each ribbon near its end is provided with a knot, rivet or other projection 236 (Figures 21 and 22), which is of too large a diameter to pass through the slotted pin 235. Accordingly, 45 when this knot encounters the slotted pin 235 the motion of the ribbon will raise the pin, and with it the arm 233 and button 232 thereon. The raising of the button 232 permits the upper portion of the bellcrank lever 229 to rise, under 50 the influence of the coil spring 227 around the pin 221 (Figure 24). Similarly, the lower flange 225, on the pin 222, is engaged by one end of an irregularly shaped bellcrank 237. This lever 237, however, remains inside the frame formed 55 by the end plate 224 and the side plates 202, as shown in Figure 25. The bellcrank lever 237 is likewise pivoted on the ribbon shaft 157, and continues upwardly along the opposite side plate 202 (Figures 21 and 22).

60 The upper edge of the bellcrank lever 237 is similarly engaged by a button 238 upon an arm 239, pivoted on the shaft 234 to the side plate 202, and similarly, having a slotted pin 240 upon its outer end adapted to be engaged by a knot 65 236 near the end of that ribbon, in a manner similar to that previously described in connection with the slotted pin 235. The arm 233 is attached to a bushing 241, surrounding the pivot shaft 234 and having an arm 242 at the opposite end of the bushing 241 (Figure 19). Similarly, the arm 239 is attached to a bushing 243, mounted upon the pivot shaft 234 and having a similar arm 244 at the opposite end of the bushing. A coil spring 245 is secured at one end to a pin 70 246 on each of the arms 242 or 244, and encircles

the bushing 241 or 243, its opposite end being anchored in the hole 247 in the upper end plate 248 joining the side plates 202. The upper end plate 248 is attached to the cross bar 125. Accordingly, when the arm 239 is raised by 5 the engagement of the knot 236 of the moving ribbon upon the slotted pin 240, the button 238 will move upward, permitting the bellcrank lever 237 likewise to move upward, under the influence of the coil spring 227 surrounding the pin 222. 10

It will be understood, however, that when the bellcrank lever 229 and its pin 221 are in their "down" position, the bellcrank lever 237 and the pin 222 will be in the "up" position, and vice versa (Figure 24). The upper end of one of the 15 pins 221 or 222 is thus brought into close proximity with the barrel of the sliding gear 209, the pin 221 being adapted to engage the cam portion 219 and the pin 222 the cam portion 220. One of these pins engages its corresponding cam portion, 20 the cam portion being of spiral form, encircling the barrel of the sliding gear 209, will urge the sliding gear longitudinally along its shaft in one direction or the other, depending upon which of the pins is in engagement. Accordingly, the sliding gear 209 will be shifted in this manner by reason of its own rotation until its toothed portion 208 engages the teeth on the spool 194, or else the toothed portion 207 engages the teeth on the spool 193. Only one of the spools is thus 30 driven at a given time, hence, the ribbon is fed freely from the spool which is not driven, and is drawn through its course, previously described, and over the various guide rollers to the driven spool. When the ribbon approaches the end of 35 its course, the knot 136 will raise the arm 223 or 239, as the case may be, causing the sliding gear 209 to be shifted by the action of the bellcrank levers 229 or 237 and the pins 221 or 222, respectively. The ribbon-driving mechanism of the 40 left-hand assembly, shown in Figure 4, is substantially identical with that on the right-hand side, which has just been described, its driving gears 210, 211, 213 and 215 being on the side plate 202 nearest the middle of the machine, as shown 45 in Figure 4.

Operation

The operation of each of the individual subassemblies or groups of mechanism in the machine 50 has been described in connection with the disclosure of the construction thereof. In the general operation of the machine the paper webs 99 are drawn upwardly through the cutaway portion 100 in the table top 95 (Figure 6), over the rod 101 and beneath the platen 34, the gripping rollers 38 having been released by operating the hand lever 41 (Figure 2). The paper webs 99 are threaded between the separate courses of the duplicating or copying ribbons 195 and 198, the 60 ribbon carriage 175 having been raised to its upper position (Figure 2), with the latches 176 in the notches 177. The master ribbon 21, however, does not make direct contact with the paper webs 99, but serves to supply ink to the type bars 20 65 with a wiping action as the type bars 20 move upward past it to engage the webs 99. Accordingly, none of the webs 99 is threaded between the master ribbon 21 and the type bars 20. After the threading has been completed the ribbon carriage is 70 lowered into the position shown in Figure 3, with the latches 176 in the notches 178. During this procedure it is assumed that the manifolding device as a whole has been lowered into engagement with the platen, with the arcuate slot 172 75

(Figure 11) surrounding the platen shaft 43, and with the platen gear 173 in mesh with the idler gear 165. If the meshing is not exact the screw 169 is loosened and the idler quadrant 167 moved 5 to one side or the other around the axis of the shaft 139 until exact registry is obtained, whereupon the screw 169 is again tightened. It is also assumed that the ribbons 195 and 198 have been threaded through their guide portions, in the 10 manner described in connection with the construction thereof.

With the machine in its lowered position the notch 249, in the lower edge of the left-hand frame side member 105 (Figure 6), rests upon the 15 pin 250 (Figure 16) in the platen frame plate 35. The paper webs 99 are now fed upwardly through the space between the ribbon carriage 175 and the frame cross bar 125, the file punch holes being placed upon the lugs 134 on the sprocket 20 chains 133 and held in position by the guide rods 205. The hand lever 155 is set in the position for single or double spacing, as may be desired, according to the manner described in connection with this construction.

25 The tabulating machine is now started in operation, according to the usual manner known to those skilled in the art, and controlled by the manipulation of the buttons 9, 10, 11, 15, 16 and 17, and such other control levers or buttons as 30 are necessary in the operation of this machine. The clutch lever 19 (Figures 1 and 2) is set in its right-hand position, marked "List" so that the printing section 14 of the machine will operate. As the machine sorts the punched cards 5 and 35 summarizes their data, the data will be printed upon the paper webs 99 by the operation of the type bars 20 within the printing section 14, in connection with the master ribbon 21, and the manifolding device ribbons 195 and 198 threaded 40 between the webs 99.

Before a printing operation starts, the rocker shaft 70 (Figure 17) is tilted by the mechanism within the printing section 14 so that the link 68 is pulled downward, moving the lever 87 outward 45 and permitting the motor and clutch control lever 121 to move outward. This action opens the clutch within the casing 116, opens the switch and deenergizes the motor 113, thereby stopping the motion of the platen, ribbons and paper webs. 50 With the motor clutch opened the motor 113 spins to a stop, and the printing operation is carried out by the motion of the type bars 20 against the various ribbons.

As the printing operation ceases the rocker shaft 70 tilts in the opposite direction, permitting the link 68 to move upward, causing the lever 87 to move inward (Figure 17). This pushes the motor and clutch control lever 121 inward, closing the motor switch and also the clutch. The 55 motor 113 is thereby energized and starts rotating, and the output shaft 120 (Figure 31) is directly connected to the motor through the worm gearing within the casing 116. As the output shaft 120 starts rotating the ribbons 195 and 60 198 immediately begin to move, but the paper webs 99 remain stationary until the gear pin 141 on the gear 140 engages the pawl-operating arm 144 and raises the pawl 146, thereby moving the ratchet wheel 147 on the sprocket shaft 139. 65 The sprocket chains 133 and their lugs 134 begin to move upward, likewise moving the paper webs through one space. The mechanism within the casing 116 is of such a nature, as disclosed in the previously mentioned Pfeiffer Patent No. 70 1,825,418, that a complete cycle of operations is

carried out regardless of when the motor control lever 121 is released.

The paper webs stop moving as the gear pin 141 (Figure 31) releases the pawl-operating arm 144, but the ribbons continue to move because their driving shaft 157 is connected, through the gears 144 and 143, to the gear 140 on the output shaft 120, which is still rotating. By this means the ribbons 195 and 198 are caused to start moving while the paper webs 99 are still 10 stationary, and continue moving after the paper webs have come to a halt. This previous motion of the ribbons breaks up any tendency toward adhesion between the ribbons and the paper webs, and prevents the "bowing up" of the ribbons which occurs without such provision. The "bowing up" of the ribbons, which otherwise occurs, pulls the ribbons out of registry with the type bars and prevents the copies from being made. Meanwhile, the platen 34 has been rotated through one space, by the action of its gear 173 being driven through the idler gear 165 from the gear 161 on the sprocket shaft 139 (Figure 11). The platen, however, merely acts 15 as an idler because the gripping rollers 38 are 20 held out of engagement with the platen.

After the motor 113 has caused the apparatus to move the paper webs through a complete space, it comes to a halt and the rocker arm 70 tilts in the opposite direction, starting another 30 printing operation. In this manner the printing operation and the ribbon and paper moving operations occur alternately and intermittently so that the paper webs 99 and the ribbons 195 and 198 are always stationary during the printing 35 operation.

The modification shown in Figure 41 is similar to the construction shown in Figure 32, but additionally employs carbon strips 295 to produce copies in excess of the number produced by the 40 copying ribbons 21, 195 and 198 alone. The carbon strips 295 are interleaved between the paper webs 99, and are preferably continuous carbon webs. These carbon webs may be unrolled from and rerolled upon suitable rollers 45 driven by conventional mechanism (not shown). It will be understood, however, that carbon sheets may optionally be employed, with conventional stripping mechanism (not shown) for returning the sheets to a position interleaved between un- 50 typed portions of paper webs after the portions they previously engaged have been typed.

We desire to comprehend within our invention such modifications as may be embraced within the claims and the scope of the invention. 55

Having thus fully described our invention, what we claim as new and desire to secure by Letters Patent, is:

1. In combination, a machine arranged to print a record, printing means on said machine, a plurality of ribbons interleaved between record sheets, means for moving the record sheets, means for moving the ribbons, and means for causing the ribbons to commence their motion before the record sheets begin to move and to 60 continue to move while said record sheets are moving.

2. In combination, a machine arranged to print a record, printing means on said machine, a plurality of ribbons interleaved between record 70 sheets and arranged to move transversely to the direction of motion of said record sheets, means for moving the record sheets, means for moving the ribbons, and means for causing the ribbons to commence their motion before the record 75

sheets begin to move and to continue to move while said record sheets are moving.

3. In combination, a machine arranged to print a record, printing means on said machine, a plurality of ribbons interleaved between record sheets, means positively engaging said record sheets for moving the record sheets, means for moving the ribbons, and means for causing the ribbons to commence their motion before the record sheets begin to move and to continue to move while said record sheets are moving.

4. In combination, a machine arranged to print a record, printing means on said machine, a plurality of ribbons interleaved between record sheets, means extending through apertures in the record sheets to positively engage and move said sheets, means for moving the ribbons, and means for causing the ribbons to commence their motion before the record sheets begin to move and to continue to move while said record sheets are moving.

5. In combination, a machine arranged to print a record, printing means on said machine, a plurality of ribbons interleaved between record sheets, means for moving the record sheets, means for moving the ribbons, and means for causing the ribbons to commence their motion before the record sheets begin to move and to continue to move while said record sheets are moving, each ribbon being arranged to pass across and back between the record sheets so that the separate courses thereof permit a plurality of copying impressions to be made.

6. In combination, a machine arranged to print a record, printing means on said machine, a plurality of ribbons interleaved between record sheets, means positively engaging said record sheets for moving the record sheets, means for moving the ribbons, and means for causing the ribbons to commence their motion before the record sheets begin to move and to continue to move while said record sheets are moving, each ribbon being arranged to pass across and back between the record sheets so that the separate courses thereof permit a plurality of copying impressions to be made.

7. In combination, a machine arranged to print a record, printing means on said machine, a plurality of ribbons interleaved between record sheets, means for moving the record sheets, means for moving the ribbons, means for causing the ribbons to commence their motion before the record sheets begin to move and to continue to move while said record sheets are moving, and means responsive to the arrival of the ribbons at predetermined positions for reversing the direction of travel of said ribbons.

8. In combination, a machine arranged to print a record, printing means on said machine, a plurality of ribbons interleaved between record sheets, means for moving the record sheets, means for moving the ribbons, means for causing the ribbons to commence their motion before the record sheets begin to move, and means interconnecting said printing means and said record moving means for causing one means to move while the other means remains stationary.

9. In combination, a machine arranged to print a record, printing means on said machine, a plurality of ribbons interleaved between record sheets, means for moving the record sheets, means for moving the ribbons, and means for causing the ribbons to commence their motion before the record sheets begin to move and to

continue their motion after the record sheets cease moving.

10. A manifolding attachment for a record printing machine comprising a frame adapted to register with the printing portion of said machine, power-operated means for supporting and moving a plurality of record sheets, a plurality of ribbons interleaved between said record sheets, power-operated means for moving said ribbons, and means synchronized with the printing mechanism of the machine and responsive to the power operation thereof for causing the power-operated ribbon-moving and record-sheet-moving means to remain stationary while the printing mechanism is making an imprint upon said record sheets. 10

11. A manifolding attachment for a record printing machine comprising a frame adapted to register with the printing portion of said machine, means for supporting and moving a plurality of record sheets, a plurality of ribbons interleaved between said record sheets, means for moving said ribbons, means synchronized with the printing mechanism of the machine for causing the ribbon-moving and record-sheet-moving means to remain stationary while the printing mechanism is making an imprint upon said record sheets, and means for causing the ribbons to commence their motion before the record sheets begin to move. 15

12. A manifolding attachment for a record printing machine comprising a frame adapted to register with the printing portion of said machine, means for supporting and moving a plurality of record sheets, a plurality of ribbons interleaved between said record sheets, means for moving said ribbons, means synchronized with the printing mechanism of the machine for causing the ribbon-moving and record-sheet-moving means to remain stationary while the printing mechanism is making an imprint upon said record sheets, and means for causing the ribbons to commence their motion before the record sheets begin to move. 20

30

13. A manifolding attachment for a record printing machine comprising a frame adapted to register with the printing portion of said machine, power-operated means for supporting and moving a plurality of record sheets, a plurality of ribbons interleaved between said record sheets, power-operated means for moving said ribbons, and means synchronized with the printing mechanism of the machine and responsive to the power operation thereof for causing the power-operated ribbon-moving and record-sheet-moving means to remain stationary while the printing mechanism is making an imprint upon said record sheets. 35

50

14. A manifolding attachment for a record printing machine comprising a frame adapted to register with the printing portion of said machine, power-operated means for supporting and moving a plurality of paper webs, said webs having apertures adapted to be positively engaged by said web-moving means, a plurality of ribbons interleaved between said paper webs, power-operated means for moving said ribbons, and means synchronized with the printing mechanism of the machine and responsive to the power 60

65

70

75

75

operation thereof for causing the power-operated ribbon-moving and web-moving means to remain stationary while the printing mechanism makes an imprint upon the paper webs.

15. A manifolding attachment for a record printing machine comprising a frame adapted to register with the printing portion of said machine, means for supporting and moving a plurality of paper webs, said webs having apertures adapted to be positively engaged by said web-moving means, a plurality of ribbons interleaved between said paper webs, means for moving said ribbons, means synchronized with the printing mechanism of the machine for causing the ribbon-moving and web-moving means to remain stationary while the printing mechanism makes an imprint upon the paper webs, and means for causing the ribbons to commence their motion before the paper webs begin to move.

20. 16. A manifolding attachment for a record printing machine comprising a frame adapted to register with the printing portion of said machine, a pair of ribbon holders mounted on said frame, a ribbon having its opposite ends on said holders, guiding means arranged to guide the ribbon across said frame and back again so as to permit two copies to be printed simultaneously by a single ribbon, means for moving a plurality of record sheets interleaved with said ribbon, and means for moving said ribbon arranged to cause said ribbon to commence its course before the record sheets begin to move and to continue to move while said record sheets are moving.

25. 17. A manifolding attachment for a record printing machine comprising a frame adapted to register with the printing portion of said machine, a pair of ribbon holders mounted on said frame, a ribbon having its opposite ends on said holders, guiding means arranged to guide the ribbon across said frame and back again so as to permit two copies to be printed simultaneously by a single ribbon, means for moving a plurality of record sheets interleaved with said ribbon, and means for moving said ribbon arranged to cause said ribbon to commence its course before the record sheets begin to move and to continue its course after the record sheets cease moving.

30. 18. In a manifolding device, a platen, means for moving said platen, means for printing upon record sheets held by said platen, a frame, a pair of ribbon holders associated with said frame, a ribbon having its opposite ends on said holders, means for guiding said ribbon in a plurality of sections to and fro across said frame in front of said platen, means for supporting and moving a plurality of carbon sheets interleaved between said ribbon sections, and means for moving said ribbon arranged to cause the ribbon to commence its motion before the record sheets begin to move and to continue to move while said record sheets are moving.

35. 19. A manifolding attachment for a machine having record printing means therein comprising a frame adapted to register with the printing portion of said machine, a motor mounted on said frame, means operated by said motor for moving a plurality of record sheets through the attachment, means for moving a ribbon having a plurality of sections interleaved between said sheets, and means responsive to the starting and stopping of said printing means for causing the stopping and starting, respectively, of said record sheet and ribbon-moving means.

40. 20. A manifolding attachment for a machine having record printing means therein comprising

a frame adapted to register with the printing portion of said machine, a motor mounted on said frame, means operated by said motor for moving a plurality of record sheets through the attachment, means for moving a ribbon having a plurality of sections interleaved between said sheets, and means responsive to the starting and stopping of said printing means to stop and start said motor so as to stop and start said record sheet and ribbon-moving means.

45. 21. A manifolding attachment for a machine having record printing means comprising a frame adapted to register with the printing portion of said machine, a carriage movable on said frame, a plurality of ribbons guided across said carriage, means for moving said ribbons, means on said frame for supporting and moving a plurality of record sheets interleaved with said ribbons, and means for causing the ribbons to commence their motion before the record sheets begin to move and to continue to move while said record sheets are moving.

50. 22. A process of making multiple impressions upon record sheets by duplicating members, comprising moving said duplicating members and after the commencement of said duplicating member motion, moving said record sheets into printing position while continuing to move said duplicating members, and printing the multiple impressions upon said sheets, whereby to prevent adhesion between said duplicating members and said record sheets.

55. 23. A process of making multiple impressions upon record sheets by copying ribbons, comprising moving said ribbons relatively to said record sheets while holding said record sheets stationary, moving said record sheets into printing position while continuing to move said ribbons after said ribbons have begun to move, and printing the multiple impressions upon said sheets, whereby to prevent adhesion between said ribbons and said record sheets.

60. 24. A process of making multiple impressions upon record sheets by copying ribbons, comprising moving said ribbons relatively to said record sheets while holding said record sheets stationary, moving said record sheets into printing position after said ribbons have begun to move, halting said record sheets and continuing the motion of said ribbons after the halting of said record sheets, and printing the multiple impression upon said sheets whereby to prevent adhesion between said ribbons and said record sheets.

65. 25. A manifolding attachment for a record printing machine, comprising a frame adapted to register with the printing portion of said machine, a pair of shafts supported by said frame, sprockets on said shafts, sprocket chains drivingly interconnecting said sprockets, means on said sprocket chains adapted to positively grip a plurality of record sheets, a plurality of ribbons adapted to be interleaved between said sheets, means for moving said ribbons, means for rotating one of said sprocket shafts to move said record sheets, and means responsive to the operation of the printing portion of said machine to halt said sprocket shaft and said ribbon-moving means during the printing operation.

70. 26. A manifolding attachment for a record printing machine, comprising a frame adapted to register with the printing portion of said machine, a pair of shafts supported by said frame, sprockets on said shafts, sprocket chains drivingly interconnecting said sprockets, means on said sprocket chains adapted to positively grip a

- plurality of record sheets, a plurality of ribbons adapted to be interleaved between said sheets, means for moving said ribbons, means for rotating one of said sprocket shafts to move said record sheets, means responsive to the operation of the printing portion of said machine to halt said sprocket shaft and said ribbon-moving means during the printing operation, and means arranged to actuate said ribbon-moving means
- 5 27. A ribbon-driving assembly for typing machines, comprising a pair of rotatable ribbon holders, a gear arranged to rotate each ribbon holder, a sliding gear arranged to mesh selectively with one of said ribbon holder gears at a given time, means for driving said sliding gear, a cam device associated with said sliding gear, a pair of movable members engaging the ribbon from each of said holders, cam-engaging means adapted selectively to engage said cam means to slide said gear, and means operatively connecting said movable members to said cam-engaging means, each of said movable members being adapted to be shifted by the arrival thereof at an obstruction at a predetermined part of said ribbon, whereby to reverse the direction of motion of said ribbon.
- 10 28. A ribbon-driving assembly for typing machines, comprising a pair of rotatable ribbon holders, a gear arranged to rotate each ribbon holder, a sliding gear arranged to mesh selectively with one of said ribbon holder gears at a given time, means for driving said sliding gear, cam means arranged to shift said sliding gear, a pair of movable members engaging the ribbon from each of said holders, and means operatively connecting said movable members to said cam means to shift said gear, said movable members being adapted to be shifted by the arrival thereof at an obstruction at a predetermined part of said ribbon, whereby to reverse the direction of motion of said ribbon.
- 15 29. A manifolding device for producing multiple copies of record sheets, a plurality of type-bearing members, a plurality of copying ribbons, a platen, means for intermittently moving said platen and said ribbons while halting said type-bearing members and vice versa, and means for causing said ribbons to commence motion before said platen begins to move, whereby to prevent the record sheets from dragging the ribbons out
- 20 30. In combination, means for feeding two record sheets, means for feeding transversely thereof a duplicating ribbon therebetween at right angles to the line of movement of the record sheets, and means to move said ribbon before and during the motion of the record sheets.
- 25 31. In combination, means for feeding two record sheets, means for feeding transversely thereof a duplicating ribbon therebetween at right angles to the line of movement of the record sheets, means to move said ribbon when the record sheets are at rest and to continue to move said ribbon while the record sheets are moving.
- 30 32. In a record printing machine, an inking ribbon, a type-bearing member arranged to engage said ribbon, a support for the record sheets to be printed, a copying ribbon interleaved between the record sheets, a motor for moving the inking ribbon, and an independent motor for
- 35 33. In a record printing machine, an inking ribbon, a type-bearing member arranged to engage said ribbon, a support for the record sheets to be printed, a copying ribbon interleaved between the record sheets, a motor for moving the inking ribbon, an independent motor for moving the copying ribbon, and means arranged to interconnect said motors to operate the same in timed relationship.
- 40 34. In a record printing machine, a type-bearing member, means for actuating said type-bearing member, a copying ribbon, means for moving said copying ribbon, a record sheet support arranged adjacent said copying ribbon, and mechanism associated with said record sheet support to afford interconnecting said type-bearing member actuating means with said copying ribbon moving means, said mechanism comprising means responsive to the actuation of said type-bearing member for operatively disconnecting said ribbon-moving means from said ribbon.
- 45 35. In a record printing machine, a type-bearing member, means for actuating said type-bearing member, a copying ribbon, means for moving said copying ribbon, a platen, means for rotating said platen alternately with the actuation of said type-bearing member, and mechanism associated with said platen for interconnecting said platen-rotating mechanism with said copying ribbon-moving means.
- 50 36. In a record printing machine, a type-bearing member, means for actuating said type-bearing member, a copying ribbon, a motor for moving the copying ribbon and the record sheets to be printed, a platen for guiding said record sheets, and mechanism associated with said platen for operatively interconnecting said type-bearing member actuating means and said motor for rendering said motor operatively ineffective for moving said ribbon and said carbon sheets during the motion of said type-bearing member.
- 55 37. In combination, a machine arranged to print upon record sheets, printing means on said machine, an ink ribbon, means positively engaging and holding said record sheets together in alignment while moving them, means for moving the ribbon, and means for causing the ribbon to commence to move while the record sheets are stationary and to continue to move while the record sheets are moving.
- 60 38. In combination, a machine arranged to print upon record sheets, printing means on said machine, a ribbon interleaved between said record sheets, a carbon strip additionally interleaved between said record sheets, means for moving the record sheets, means for moving the ribbon, and means for causing the ribbon to commence to move while the record sheets are stationary and to continue to move while the record sheets are moving.
- 65 39. In combination, a machine arranged to print upon record sheets, printing means on said machine, a ribbon interleaved between said record sheets, a carbon strip additionally interleaved between said record sheets, means for moving the record sheets, means for moving the ribbon adapted to cause the ribbon to start moving before the record sheets begin to move and to continue to move while the record sheets are moving, and means for moving the carbon strip to different portions of said record sheets.
- 70 40. In combination, a machine arranged to print upon record sheets, printing means on said machine, a ribbon interleaved between said record sheets, a carbon strip additionally interleaved

between said record sheets, means for moving the record sheets, means for moving the ribbon adapted to cause the ribbon to start moving before the record sheets begin to move and to continue moving after the record sheets cease moving, and means for moving the carbon strip to different portions of said record sheets.

41. In combination, a machine arranged to print upon record sheets, printing means on said machine, a ribbon interleaved between said record sheets, a carbon strip additionally interleaved between said record sheets, means for moving the record sheets, means for moving the ribbon adapted to cause the ribbon to start moving before the record sheets being to move and to continue to move while the record sheets are moving, and means for maintaining said record

sheets in aligned registration with one another during their motion, whereby to permit the employment of multiple printed forms in aligned registration with one another during their motion.

42. A process of making multiple impressions upon record sheets by a copying ribbon comprising moving a copying ribbon, thereafter moving the record sheets to the printing position while continuing to move the copying ribbon, halting the record sheets, and thereafter continuing to move the copying ribbon whereby to prevent adhesion of the copying ribbon or its displacement by the motion of said record sheets.
